UNITED STATES PATENT OFFICE.

WILLIAM S. GRUBB, OF BARABOO, WISCONSIN.

FISH-PLATE FASTENING.

SPECIFICATION forming part of Letters Patent No. 317,531, dated May 12, 1885.

Application filed January 31, 1885. (No model.)

To all whom it may concern:

Be it known that I, WILLIAM S. GRUBB, of Baraboo, county of Sauk, and State of Wisconsin, have invented certain new and useful Improvements in Fish-Plate Fastenings, of which the following is a full, clear, and exact description, reference being had to the accompanying drawings, and to letters of reference marked thereon.

My invention has relation to fastenings for the plates applied upon or in connection with the meeting ends of railway-rails, and ordinarily known as "fish-plates." Heretofore these fish-plates have been ordinarily secured to the rails by bolts passing through the plates and rails, various forms of nuts and lock-nuts being applied with a view to preventing accidental disarrangement. The perforations required weaken the plates and the rails, and the security and support required are not always afforded.

The object of my invention is to secure the plates in a thorough manner without requiring perforations in either the rails or the plates. This I accomplish by employing one or two chairs at each joint, the same being made to pass under the rail and to extend up on each side thereof, so as to afford a bearing against the plate on one side and so as to sustain a wedge or key, which can be jammed up tightly against the plate on the other side, and my improvements involve certain novel and useful peculiarities of construction and relative arrangements or combinations of parts, all of which will be herein first fully described, and then pointed out in the claims.

In the accompanying drawings, forming part of this specification, Figure 1 is a side elevation, Fig. 2 a top or plan view, Fig. 3 a cross-section through the middle of the chair, and Fig. 4 an end elevation, all showing my improvements applied in connection with the meeting ends of railway-rails. Figs. 5, 6, 7, and 8 are views similar to Figs. 1, 2, 3, and 4, respectively, showing the wedge inclined on its inner edge, instead of on its outer edge, as in previous figures, omitting the locking-block and showing a wearing-plate between the wedge and the fish-plate.

In all these figures like letters of reference, wherever they occur, indicate corresponding parts.

A is the railway-rail or track, the joints in which are to be supported and secured. B are the fish-plates, one on each side of the joint. C 55 is a chair, of iron, made amply strong, one end of which is fashioned so as to enter a slight recess in the fish-plate, to keep the latter from rising or creeping in either direction. On the other side is a wedge or key, D, having a 60 threaded projection, d, on which is a nut, a, for drawing the wedge into its proper place or holding it therein after adjustment. Upon the fish-plate is a perforated lug or projection, b, through which the neck d passes and against 65 which the nut a is made to bear. The wedge D bears against the fish-plate and against the chair in a manner which will be readily understood. By turning the nut the pressure of the wedge may be increased to any desired extent. 70

In Fig. 2 the wedge is shown as inclined on its outer edge or side, the bearing-face of the chair being correspondingly inclined and the inner face of the wedge being straight. In 75 Fig. 6 the outer edge or side of the wedge is shown as straight, while the inner face is inclined, as is also the channel in the fish-plate, as indicated by dotted lines. In both forms the principle of operation is the same. 80

At Fig. 7, is a piece of soft iron or metal, applied between the wedge and the fish-plate, to afford a perfectly secure joint. This might be omitted, if desired.

At f, Figs. 1 and 2, is a locking-block, slotted longitudinally, passing over a threaded bolt, g, and held in place by a nut, h. The inner face of this block and the adjacent part of the fish-plate are preferably furrowed, as indicated by dotted lines in Fig. 2, to prevent 90 any slipping. When the wedge is drawn tightly to place, the locking-block is moved up against the end thereof and secured. By this means the wedge is prevented from slipping back and the parts thereby thoroughly 95 locked in place.

I have shown a single fastening applied at the joint, and this is the preferred construction; but obviously one chair might be located near one end of the plate and another near the 100 other end, the wedges being made to draw in opposite directions.

In this method of fastening the fish-plates and thus securing the joints in the rails, ex-

pansion and contraction of the rails will not injuriously affect the security of the joints, and the cutting or punching of oblong slots in the plates or the perforating of the rails for the passage of bolts is entirely obviated.

The threaded portions of the wedges extend in the direction of the length of the rails, and the nuts thereon are not liable to be jarred loose, as in cases where the bolts pass through the rails.

The plates may be made shorter than in other constructions, and still afford all the desired stability and security, without any material increase in the cost of construction and application.

Having now fully described my invention, what I claim as new herein, and desire to secure by Letters Patent, is—

1. In a fish-plate fastening, the chair extending under the rails and up on both sides and the wedge bearing against one plate and against the chair, said wedge having a threaded neck

and nut, and a bearing for the nut, these parts being arranged and combined substantially as and for the purposes set forth.

2. The combination, with the longitudinally-moving wedge, the chair, and the fish-plate, of the adjustable locking-block, substantially as and for the purposes set forth.

3. The combination, with the two fish-plates, of the chair passing under the rails, one part entering a recess in the plate on one side and the other part having a seat for the wedge, the wedge bearing against the second plate, the nut, and the bearing therefor, arranged substantially as shown and described.

In testimony that I claim the foregoing I have hereunto set my hand in the presence of two witnesses.

WM. S. GRUBB.
